(57) **CLAIM**

The ornamental design for a toothbrush, as shown and described.

DESCRIPTION

FIG. 1 illustrates a top plan view of a toothbrush showing the new design;

FIG. 2 illustrates a bottom plan view thereof;

FIG. 3 illustrates a front elevation view thereof;

FIG. 4 illustrates a back elevation view thereof;

FIG. 5 illustrates a side elevation view thereof, the opposite side elevation view being a mirror image thereof; and,

FIG. 6 illustrates a perspective side view thereof.

The ovals shown on the vertical surfaces of the toothbrush in FIGS. 3, 5 and 6 (three on each side portion and three on the portion with the handle), are openings. The ovals shown on the floor surfaces of the toothbrush in FIGS. 1 and 2 (2 on each side and one directly in front of the handle) are also openings.
